NAIL CLIPPERS

Boonyium Meesook, Hudson Falls, N. Y.

Application August 31, 1946, Serial No. 694,264

1 Claim. (Cl. 30—124)

1

The present invention relates in general to a cutting tool and more particularly to an improved clipper for manicuring nails and cuticle, and is a continuation in part of a co-pending application, Serial No. 598,866 filed June 11, 1945, now abandoned.

An object of the invention is to provide a clipper with improved means to retain small cuttings during the clipping operation.

A further object of the invention is to provide an improved manicure clipper which is adapted to prevent the indiscriminate scattering of bits of severed nail and cuticle.

A still further object is to provide an improved manicure clipper having a transparent guard arranged to form a closed pocket in which small bits of nail and cuticle will collect during the normal use of the clipper and from which the small bits of nail and cuticle may be readily removed in a neat and sanitary manner.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a plan view of the bottom face of the improved manicure clipper of this invention, the jaws of which are closed.

Fig. 2 is a front elevation of the clipper shown in Fig. 1;

Fig. 3 is an elevation of the left-hand end of the clipper shown in Fig. 2;

Fig. 4 is a fragmentary perspective view of the clipper-jaws in open position, the pocket of the clipper being in the position it has during the manicuring operation;

Fig. 5 is a section of the clipper-jaws on line 5—5 of Fig. 1, the jaws being in closed position;

Fig. 6 is a section similar to Fig. 5 but with the clipper inverted and the jaws open; and

Fig. 7 is a perspective view of the guard-member which is adapted to be cooperatively associated with the jaws of the clipper to form a confined recess and pocket for retaining small pieces of nail and cuticle.

Referring to the drawings which show an exemplary embodiment of the invention, the clipper, indicated generally at 10, is a relatively-lightweight-type of clipper used for the purpose of manicuring nails and cuticle and comprises a pair of operating-handles 11 and 12 having corresponding fulcrum-portions 13 and 14 which are

2

joined together by the usual lap-joint and pivot-pin indicated generally at 15. Each fulcrum-portion 13 and 14 is provided at its outer extremity with a jaw 16 and 17 respectively, having mutually-coacting cutting-edges 18 and 19 respectively which, as seen in the horizontal plane of Fig. 1, are substantially straight and in the plane of the upper faces of the jaws. Clippers of this type are quite generally provided with a leaf-spring or other equivalent resilient-means secured at one end to one of the handles of the clipper and adapted to resiliently engage the opposite handle, so that the jaws are normally held open. In the present embodiment, the handle 12 is provided with an apertured boss 20 for pivotally securing one end of a leaf-spring 40 thereto.

To adapt the jaws for manicuring purposes, the upper face 21 and 22 respectively of each jaw is 20 of concave curvature, as indicated in Figs. 2 and 3, as a consequence of which the cutting-edges 18 and 19 of the jaws have a corresponding curvature, as shown in Figs. 2 and 4 for guiding the clippers and insuring a smoothly-curved cut on 25 nails and cuticle.

The bottom faces of the jaws constitute sloping-surfaces or walls which, as shown at 23 and 24 respectively in Figs. 5 and 6, extend from the outer edges of the corresponding jaws inwardly 30 and upwardly to the respective mutually-coacting cutting-edges 18 and 19 thereof. These sloping-walls, together with the substantially-vertical walls 25 and 26 at the inner ends of each respective jaw, form a substantially-V-shaped 35 relief-recess when the jaws are closed, as indicated generally at 27 in Fig. 5.

Arranged to cooperate with the relief-recess 27 is a guard or cover-member indicated generally at 28 in Fig. 7, which comprises relatively-thin sheet material such, for example, as Celluloid or a transparent plastic, or it may be thin sheet metal, having a substantially-rectangular tongue-portion 29 at one end provided with a centrally-arranged aperture 30 adapted to receive 45 fastening-means represented by a screw 31 for securing the guard to the bottom face of the jaws, as shown in Fig. 1. To this end, the fulcrum-portion 13 of the one jaw 16 of the clipper is provided with a substantially-rectangular relatively-shallow groove 32, the over-all dimensions of which correspond substantially to those of the tongue-portion 29 of the guard. The latter is thus adapted to seat snugly in the groove 32 and to be secured therein substantially flush with 50 the plane of the fulcrum-portion 13 of the jaw by 55

the screw 31 which is threadedly engaged in an aperture 33 in the fulcrum-portion 13. The guard-member has a forwardly-extending cover-portion identified at 34, shaped substantially like an isosceles triangle, the base of which is slightly wider than the tongue-portion 29 of the guard and forms therewith two substantially-square shoulders 35 on opposite sides of the guard, these shoulders 35 being adapted to abut corresponding shoulders 36 and 37 respectively of the fulcrum-ports 13 and 14 of the jaws, as shown in Fig. 1, to prevent pivotal movement of the guard. The sides 38 of the cover-portion 34 of the guard are coincident with the bottom edges of the jaws 16 and 17 and converge to a point which, as shown in the drawings, coincides with the pointed extremity of the jaws 16 and 17, the sides 38 being curved from the horizontal plane of the tongue-portion 29 of the guard upwardly in conformity with the upward curvature of the bottom edges of the jaws, as shown in Figs. 2 and 4.

It will be clear that the guard 28 is secured to one jaw only of the clipper and comprises a single continuous cover-member which extends from the outer edge of the jaw 16 to the outer edge of the jaw 17 when the jaws are closed, the continuous cover-member spanning the mutually-coacting cutting-edges 18 and 19 of the jaws, thereby completely enclosing the relief-recess 27, as shown in Fig. 5.

In operating the clipper, the clipper is held so that the jaw 16 to which the guard 28 is fastened is undermost, whereby the cover-portion 34 of the guard forms with the corresponding sloping-side 23 of the jaw 16 a pocket 39 within which the nail and cuticle cuttings are adapted to be caught during operation of the clipper, the cover-portion 34 also serving to prevent indiscriminate scattering of the trimmings. Following the trimming operation, the operator inverts the clipper and opens the jaws thereof, whereupon by a series of sharp jerks or light tappings the short pieces of nail and cuticle are readily removed from the pocket 39 for disposal.

The improved manicure clipper thus constitutes a neat and sanitary means which is convenient to handle and of pleasing appearance for

trimming nails and cuticle and eliminates the unsightly, unsanitary and inconvenient scattering of nail cuttings which have heretofore accompanied nail and cuticle trimming operations.

5 The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

- 15 15. In a nail clipper, the combination with a pair of pivoted operating-handles having jaws provided with mutually-coacting cutting-edges, said jaws having beveled sides arranged to form a relief-recess between said beveled sides when said 20 jaws are closed: of a longitudinal groove in the outer face of one of said jaws; a guard carried by said one jaw, said guard comprising a single continuous transparent cover-member arranged to extend from the outer edge of the one jaw to 25 the corresponding outer edge of the opposite jaw when said jaws are closed so as to span the mutually-coacting cutting-edges of said jaws and to form a pocket with said relief-recess for retaining short lengths of nail and cuticle severed 30 by said jaws; means to mount said single continuous transparent cover-member on said one jaw comprising a relatively-narrow tongue mold- 35 integral with said cover-member and dimensioned to fit snugly in the longitudinal groove of said one jaw substantially flush with the outer face thereof; and fastening-means to secure said tongue in said groove.

BOONYIUM MEESOOK.
